his Attorney

UNITED STATES PATENT OFFICE.

HAROLD C. MACAIRE, OF CHICAGO, ILLINOIS.

WATER-HEATER.

1,022,637.

Specification of Letters Patent.

Patented Apr. 9, 1912.

Application filed February 24, 1911. Serial No. 610,524.

To all whom it may concern:

Be it known that I, HAROLD C. MACAIRE, a subject of the King of England, residing at Chicago, county of Cook, and State of Illinois, have invented certain new and useful Improvements in Water-Heaters, of which the following is a specification.

My invention relates to improvements in water-heaters particularly adapted for domestic use, the object of the invention being the provision of an improved water-heater, which shall be simple of construction and efficient in operation.

The invention consists of the novel constructions and arrangement of parts all as will be hereinafter more fully described and more particularly pointed out in the appended claims.

The invention will be more readily understood by reference to the accompanying drawings, forming a part of this specification and in which,

Figure 1 is the central vertical section of a water-heater embodying my invention. Fig. 2 is a partial side elevation of the water-heater, and Figs. 3 and 4 are detail top plan views.

The preferred form of construction of my invention as illustrated on the accompanying drawings comprises a vertical boiler 1 of a common construction except as otherwise hereinafter indicated. A stand or pedestal 2 supports a circular angle-iron 3 which forms a seat for the boiler 1; and the gas-pipe 4 leading into the boiler at the lower end thereof is connected to an annular pipe or chamber 5 arranged under the boiler by means of a threaded lug 6 and pipe-connection 7. The annular chamber 5 is arranged concentric with the boiler and is designed to supply gas to a series of Bunsen burners 8 having controlling cocks 9, said burners being equally spaced on the chamber and accessible for regulating the size of the gas flames 10. A hinged door 11 is provided on one side of the boiler opposite the burners, this door being ordinarily kept closed for concealing the burners, which otherwise would detract from the general appearance of the water-heater. The boiler 1 is provided with a closed top 12 and a frusto-conical shaped bottom 13, the latter having a cylindrical flue 14 extending upwardly therefrom which is arranged in axial alignment with the boiler 1 and passed through the top 12 to atmosphere.

The water inlet-pipe 15 is arranged parallel with the flue 14 and is passed through the top 12 and thence downwardly to adjacent the bottom 13, as illustrated in Fig. 1. When the water-heater is in operation the boiler should be filled with water, but for clearness of illustration the same is indicated as only partially filled. In Fig. 1 a drain-pipe 16 extends downwardly from the bottom 13 of the boiler and is provided with a stop-cock 17. A T pipe-connection 18 is inserted in the pipe 16 just below the connection thereof with the bottom 13, and one leg of said pipe-connection is screwed into a boss 19, provided on the exterior member 20 of a hollow double-walled water-heating dome, the interior member 21 of said dome being threaded and screwed into the exterior member, as illustrated in Fig. 1. The members 20 and 21 are frusto-conical in form and the sides of the former have less angularity than those of the latter, whereby the annular conical water space is heated uniformly with the warmer water in the space between the top of the members 20 and 21, it being understood that the flames 10 are so distributed as to uniformly heat the under surface of the walls of the member 21.

Arising from a central threaded lug 22 on the top of the member 20 is a vertical water-pipe 23 which connects with a horizontal pipe 24 passed through the wall of the flue 14, said horizontal pipe 24 terminating in a T-connection 25 which is in communication with a service pipe 26 and a return flow pipe 27, water circulating through the later when the faucets of the service pipe are closed.

In order to collect the water of condensation from the pipe 23 and member 20 a peripheral trough 28 is formed in the surface of the member 20. The drip which would otherwise interfere with the action of the Bunsen burners is thus prevented.

It will be observed that the member 21 forms a trap for retaining the heat units generated by the burners, which heat will be fully utilized for heating water before it escapes.

A water-heater of the construction set forth is symmetrical in design, simple of construction, and highly efficient in operation.

While I have illustrated and described the preferred construction for carrying my invention into effect, this is capable of varia-

tion and modification without departing from the spirit of the invention, I therefore do not wish to limit myself to the precise details of construction set forth but desire to avail myself of such variations and modifications as come within the scope of the appended claims.

Having described my invention what I claim as new and desire to secure by Letters Patent is:

- 15 1. A water-heater comprising a boiler; a hollow dome located under said boiler, said dome consisting of two superposed inverted frusto-conical members, the lower of which is smaller and inserted and threaded into the upper; connections between said dome and said boiler, and means for heating said dome and said boiler, substantially as described.
- 20 2. A water heater comprising a boiler; a hollow dome located under said boiler, said dome consisting of two inverted frusto-conical members, the lower of said members having a greater angularity than the upper so as to form a water space which gradually increases in width toward the top, said lower member being threaded therein; connections between said dome and said boiler; and a

burner projecting its flame into said cavity, substantially as described.

3. A water-heater comprising a boiler; a hollow dome located under said boiler; means for heating said dome and boiler; a drain pipe for said dome, the interior of said dome being given a general inclination toward said drain pipe; and connections between said dome and said boiler, substantially as described.

4. A water heater comprising a boiler; a hollow dome located under said boiler; a burner projecting its flame into said dome; a drain pipe connected with the lower portions of said boiler and dome, the interior of said dome being given a general inclination toward said drain pipe; a stop cock in said drain pipe below said connections; and a pipe connecting the upper portion of said dome with the upper portion of said boiler, substantially as described.

In testimony whereof I have signed my name to this specification in the presence of two subscribing witnesses.

HAROLD C. MACAIRE.
